UNITED STATES PATENT OFFICE

JOHN S. WATTS, OF NEW YORK, N. Y.

FLOW NIPPLE

Application filed March 16, 1927. Serial No. 175,745.

Although my present invention is referred to simply as a flow nipple, it should be understood that the invention herein described is intended primarily for use in replacement 5 of so-called "beans", as used in the outlet pipes from flowing oil wells.

As is well understood by workers in this art, if a gushing oil well, or well containing much gas, is allowed to flow without restriction, the gas fails to bring up a maximum 10 total of oil, and the oil will moreover often bring up large quantities of sand. Unless the flow is artificially restricted, the resultant caving commonly results in the choking of 15 a well after a comparatively short time, a general result being frequently a serious damage to or a complete loss of the well,—so that a new hole must be drilled, at much expense, if production is to be continued. 20 In order to get, from each well and without danger of sanding-up, as large an oil output as possible, so-called "beans" or throttling devices have heretofore been employed; but these are comparatively crude; and it is 25 an object of my invention to provide simple and improved means, permitting small and precise variations in adjustment in accordance with changes in conditions, so to control the outlets from oil wells, by varying 30 an exit passage therethrough, as to assure, under various or constantly changing conditions, a maximum output or recovery of oil therefrom.

It has heretofore been common to insert a 35 so-called "cross", or a number of crosses assembled to constitute a so-called "Christmas tree", in an outlet pipe, or in branch outlets, from flowing oil wells; and, to constitute the mentioned "beans", said crosses have, in 40 many instances, been provided with variable bushings,—assortments being kept on hand with various comparatively small holes bored therethrough. Thus, whenever the sand has begun to move unduly, a bushing having a 45 hole (say) 1/64th inch smaller than the bushing previously employed could be substituted therefore,—successive bushings being tried, if the movement of sand continued, until sand practically ceased to come. Assuming 50 but a single bean-carrying "cross" to be uti-

lized, in the described manner, each change required a closing down of the well; and, after opening up again, a three-hour run might be required to determine whether or not the hole in the bushing was of a suitable 55 size. Moreover, the holes wore away by attrition; so that, even though correctly adjusted in the beginning, a danger point might be reached before the operatives became aware of any change in conditions. 60

As compared with the above, it is an object of my invention to provide a rugged and simple flow nipple which might be referred to as a cross provided with an adjustable bean,—an outlet opening being preferably 65 disposed at right angles to an inlet opening, and additional (normally plugged) openings being provided, to facilitate assembly and replacement of parts and/or to permit of alternative connections. In flow nipples of my design, the restriction of flow can be varied more accurately and by more minute percentages than with a "bean" of the character referred to; and the regulation can moreover be done without interfering with the operation of the well. This makes it easy to obtain 70 that rate which will give the desired or maximum safe outlet; and it is also an important merit of my novel flow nipple that those parts which are liable to wear by attrition are not 75 unduly expensive,—said parts being, moreover, replaceable without disconnection of the main cruciform body containing the same 80 from the pipe line in which the same may be interposed. 85

Other objects of my invention (which may in fact be connected with either a vertical or a horizontal pipe leading from a flowing well) may be appreciated from the following description of an advantageous embodiment 90 thereof, taken in connection with the appended claims and the accompanying drawings, in which

Fig. 1 may be referred to as, for the most part, a horizontal sectional view, with parts 95 broken away.

Fig. 2 may then be referred to as a vertical sectional view, taken substantially as indicated by the line 2—2 of Fig. 1.

Fig. 3 is a partial elevational view, taken 100

substantially as indicated by the arrow 3 of Fig. 1.

Referring to the details of that specific embodiment of my invention chosen for purposes of illustration, I show at 11 a main cruciform casting, an inlet opening 12 thereof being shown as externally threaded (for connection, as by means of a coupling 13, with a vertical or horizontal pipe extending directly or indirectly from an oil well) and an outlet opening 14, disposed at right angles to the mentioned inlet opening, being shown as internally threaded (for connection with a pipe 15,—which may lead to a tank or to a gas trap or to any other preferred unit).

The main body 11 is shown as comprising a substantially cylindrical portion 16, inwardly terminating in a thick apertured partition 17,—the walls 18 of a circular or other opening through said partition being adapted rigidly to support a removable and tubular throat member 19. The latter is shown as provided with a rectangular longitudinal passage 20.

Opposite the opening in which the tubular member 19 is seated, I show a threaded opening 21 as closed by a so-called "bull plug" 22; and this opening 21 is intended to be of such size as to permit not only the insertion or replacement of the tubular "throat" member 19 therethrough (until a peripheral flange 23 on said tubular body shall engage an oppositely disposed shoulder 24, in which the partition 17 may terminate) but also the insertion, into interfitting relationship with said throat element 19, of an adjustable closure element 25. This element is shown as replaceable and as adapted slidably to advance transversely of the mentioned passage 20 in the tubular element 19.

The adjustable closure element 25 is shown as comprising a main plate 26, corresponding in length with the rather long rectangular aperture 20, and suitably spaced terminal guide and/or stop flanges 27 and 28; and the plate 26 may be provided with means, such as an integral and interiorly threaded central boss 29 extending through a corresponding opening 30 in the tubular member 19, to facilitate an adjustment of the position of the said plate and said flanges relatively to the passage 20, to control the flow of oil and/or gas therethrough.

Both of the flanges 27 and 28 being shown as rectangular, the flange 27 and the threaded boss 29 are preferably of such dimensions as to render these parts of the closure element 25 capable of insertion through the opening 21 (upon removal of the bull plug 22, or its equivalent) and the rectangular passage 20, in the tubular throat member 19,—after said member has been introduced through the opening 21, or its equivalent; and a subsequent rotation of a threaded shaft 31, extending inward through a smooth bore 32 in the

body 16 and engaging the threaded interior of said boss, may serve not only to secure the mentioned parts in their assembled relationship but to provide for the advancing and/or retracting of said closure to any desired degree, to serve the purposes of a so-called "bean", but in a manner permitting precise regulation.

The shaft 31 may be provided with any suitable means, such as a collar 33, for its retention against longitudinal movement during rotation,—said collar being shown as held between flat annular surfaces 34 and 35, respectively provided in a depression 36 and on a separable gland-carrying fitting 37, shown as retained by screws 38; and said shaft may be provided with any suitable means, such as a mere squared end 39, favorable to its rotative adjustment.

It will be appreciated that my provision of a rather long rectangular passage 20, through the tubular member 19, and my use of a closure element 25, comprising the long flat plate 26,—inwardly terminating in the rectangular flange 28, of sufficient size to overlap the edges of the passage 20—imply durability and also imply that every rotational manipulation of the shaft 31 must produce a proportionate effect in the opening or closing of said passage. The indicated shapes and lengths of the mentioned parts are favorable not only to precision but to durability, and the timely replacement of the adjustable closure element 25 (without necessitating any disconnection of pipes 13, 15) may largely obviate wear upon any of the other parts mentioned.

Although I show the tubular element 19 as provided with depressions 39, 39', suitable for engagement by any tool employed in effecting an insertion or withdrawal thereof, I prefer not to use an excessively tight or "drive" fit at 18; and the interposition of an optional key, such as that suggested at 40, may accordingly serve mainly as an aid in a centering of all parts favorably to the insertion of the shaft 31, or its equivalent, into the boss 29 upon the closure element 25.

In use, it will be understood that my flow nipples, whether used singly or in pairs or sets, may occupy any desired position or positions; and that, whether or not a plurality of said nipples are connected to the same pipe leading from a well (in a manner favorable to the replacement of parts during a diversion of flow) inflow through the passage 20 may be permitted either by way of the opening 12 or through an oppositely disposed opening 41,—shown as closed by means of a bull plug 42. If this bull plug undergoes undue erosion, by reason of its position, it can be easily and inexpensively replaced.

If desired, embodiments of my invention may be used either with or in place of so-called control casing heads, the openings 12

and 41 being, in the case last referred to, presumably disposed one above the other; and it is a matter of some interest and advantage that, if said openings are disposed in the special manner last referred to, a flow nipple of the character described may remain connected at the top of a string of tubing even when, the gas pressure having been reduced, it may be desirable to insert a string of sucker rod and/or polish rod or a pipe therethrough,—as for the continued exploitation of a well by means such as a reciprocatory pump, (or hydraulically operated pump, or an ordinary gas lift) after the natural gas pressure shall drop.

I particularly emphasize, in conclusion, the simplicity and ruggedness of my described flow nipples; the easy replacement of inexpensive parts therein,—although the elements 19, 25, and/or 42 upon which wear may be concentrated, can be formed of a very durable material or materials; the mentioned facility of precise adjustment; and the fact that replacements can be made, when necessary, without disconnecting either an inlet or an outlet pipe or interrupting the flow of oil from the well.

Although I have herein described a single complete embodiment of my invention, mentioning alternative modes of using the same, it should be understood not only that various features thereof are capable of independent use but also that numerous modifications thereof might easily be devised by workers in the art to which this case relates, without involving the slightest departure from the spirit and scope of my invention, as the same is indicated above and in the following claims.

I claim as my invention:

1. In a flow nipple for oil wells: a main body provided with an inlet opening and with an outlet opening; a separately replaceable throat element therein; and a flow-controlling element comprising a valve element which extends longitudinally of said throat element and has a face substantially parallel with the bottom of said throat element, said valve element being movable transversely.

2. In a flow nipple for oil wells: a main body provided with an inlet opening and with an outlet opening; a throat element therein; and a flow-controlling element comprising a plate which extends longitudinally within said throat element and is movable transversely thereof,—said flow-controlling element comprising an unapertured end flange which is movable across an end of said throat element.

3. In a flow nipple for oil wells: a main body provided with an inlet opening and with an outlet opening; a throat element therein; and a flow-controlling element comprising a plate which extends longitudinally within said throat element and is movable

transversely thereof,—said flow-controlling element comprising unapertured end flanges which slidably engage the respective ends of said throat element.

4. In a flow nipple for oil wells: a main body provided with an inlet opening and with an outlet opening; a throat element therein; and a flow-controlling element comprising a valve element which extends longitudinally of said throat element having a lower face substantially parallel with the bottom of said throat and being movable transversely in said throat element,—said main body being provided with an additional opening opposite one of the mentioned openings.

5. In a flow nipple for oil wells: a main body provided with an inlet opening and with an outlet opening; a throat element therein; and a flow-controlling element comprising a longitudinal valve member which extends substantially through the length of said throat element and is movable transversely thereof,—said main body being provided with two additional openings, one opposite each of the mentioned openings.

6. In a flow nipple for oil wells: a main body provided with an inlet opening and with an outlet opening; a throat element therein; and a flow-controlling element comprising a valve member having a face substantially parallel with the bottom of said throat which extends longitudinally of said throat element, said valve member being movable transversely in said throat element, and said main body being provided with an additional opening through which said flow-controlling element is bodily movable.

7. In a flow nipple for oil wells: a main body provided with an inlet opening and with an outlet opening; a throat element therein; and a flow-controlling element comprising a valve member having a face substantially parallel with the bottom of said throat which extends longitudinally of said throat element, said valve member being movable transversely in said throat element, and said main body being provided with an additional opening through which both said flow-controlling element and said throat element are bodily replaceable, without disconnecting pipes from said inlet and outlet openings.

8. In a flow nipple for oil wells: a main body provided with an inlet opening and with an outlet opening; a throat element therein; and a flow-controlling element comprising a valve member having a face substantially parallel with the bottom of said throat which extends longitudinally of said throat element, said valve member being movable transversely in said throat element, and said throat element being provided with a rectangular opening and said plate being substantially flat.

9. In a flow nipple for oil wells: a main body provided with an inlet opening and with an outlet opening; a throat element therein; and a flow-controlling element comprising a valve member having a face substantially parallel with the bottom of said throat which extends longitudinally of said throat element, said valve member being movable transversely in said throat element, and said throat element being provided with a rectangular opening and said plate being substantially flat, and said plate being provided with threaded means for its precise adjustment within said throat element.
- 5 10 15 In testimony whereof, I have hereunto set my hand at New York, New York, this 5th day of March, 1927.

JOHN S. WATTS.
